HAIR SPRING AND BALANCE WHEEL
TIMING MECHANISM

Forrest Julian Caldwell, Chicago, Ill.

Application January 8, 1948, Serial No. 1,247

2 Claims. (Cl. 73—6)

1

This application is a continuation-in-part of the application Serial No. 649,620, filed February 23, 1946, now abandoned.

This invention relates to apparatus for determining the period of vibration of a spring mass system or the number of vibrations in any interval of time made thereby wherein the number of vibrations are individually counted and the interval of time is measured, more particularly to such apparatus for determining the period of vibration of watch and clock hair springs and attached balance wheels, and it is an object of the invention to provide improved apparatus of this character.

It is a further object of the invention to provide improved apparatus of the foregoing character wherein the interval of time may be preset and the counting of the vibrations is automatically stopped at the end of the preset interval.

The accuracy of a timepiece using a balance wheel and hair spring, whether watch or clock, depends to a large extent upon the characteristics of the balance wheel and hair spring. The number of vibrations or oscillations to and fro which the balance wheel makes determines the number of revolutions made by the timepiece hands in any interval of time. Thus, if the balance wheel is vibrating too fast, the timepiece will run fast, and if the balance wheel is running too slowly, the timepiece will run slowly. During manufacture of the balance wheel and hair spring, quality materials, precision methods and skilled workmanship are used to assure as much as can be that all combinations of balance wheels and hair springs are identical with each other. Even so, there are minor variations in the mass of the balance wheel as well as minor variations in the tension or stiffness of the hair spring. Accordingly, before a hair spring and balance wheel may be assembled into a watch, the point at which the hair spring is to be held in the watch mechanism must be determined since this point determines the length of the hair spring, its spring constant, and therefore the period of vibration of the combined hair spring and balance wheel.

Heretofore, the vibrating or rating of hair springs and balance wheels has been largely a manual operation. That is to say, a skilled person picks up each hair spring and balance wheel and holds the spring at a particular point by means of a pair of tweezers. Thereafter, the balance wheel shaft is rested upon a smooth, hard surface such as glass, and the balance wheel set into motion by rotating it with a broach or

2

pointer, and the number of vibrations for an interval of time, for example one minute, are manually counted. A hair spring and balance wheel, when once manually urged into motion, will vibrate without external aid for approximately three minutes before it spends itself or comes to rest. Inasmuch as the number of vibrations which the balance wheel should make in one minute is known from the number of teeth on the various gears, if the number of vibrations for one minute exceeds the proper number, a craftsman must grip the spring at a second point, increasing the length thereof, and repeat the operation. If the number of vibrations determined by the second trial falls within the allowed tolerance, the operation is complete. However, it may be that the craftsman has gripped the spring at a point where the spring is too long and the second trial reveals that the balance wheel is running too slow. A third operation of the same character will probably determine the point at which the hair spring should be held.

The actual counting operation is tedious and nerve-racking. In a regular train watch the balance wheel makes five vibrations per second, or 300 vibrations per minute counting both the tick and tock movements. The craftsman vibrating the hair spring and balance wheel then must not only grip the very delicate hair spring with a pair of tweezers, noting that it is gripped properly so that it is not distorted, but he must start the balance wheel vibrating and begin his counting thereof at a particular time. The counting interval must be started at the same time the counting is begun, this necessitating looking at the balance wheel and the timing device at the same instant. After the operation is begun, there is the situation of having to count as many as five vibrations a second without missing any, and at the same time the timing device must be observed to note when the interval of one minute, for example, has gone by. In order to develop a sense of timing, watch hair spring vibrators frequently use such methods as stamping their foot, thereby deriving a certain rhythm tending toward accuracy.

Assuming that three trials are sufficient to determine the proper holding point for the hair spring, it is evident that even a skilled worker cannot do more than a small number of watch or clock springs in one day. Moreover, it frequently occurs that even while gripping the hair spring as best possible, after it has been gripped at a number of points, the spring itself becomes somewhat distorted near the holding point which

impairs the accuracy thereof and may even make it completely useless. Accordingly, it is a further object of my invention to provide improved apparatus for counting the vibrations of hair springs and the attached balance wheels where the counting operation and the time interval of counting may be carried out by the apparatus and the human factors are largely eliminated.

In apparatus according to one form of the invention, photoelectric means including a relatively narrow beam of light which may be interrupted by the balance wheel spoke has been provided, the light interruptions actuating means for counting the vibrations. A holding means for the watch hair spring has been provided so that the spoke of the balance wheel can vibrate into or through the beam of light. Since the hair spring is a spiral, it is evident that the point of holding the hair spring determines the orientation of the balance wheel spoke relative to the light beam. That is, if the spring, when gripped at one point, is so oriented that the balance wheel spoke vibrates into the beam of light and the point of gripping is changed, it may be that the spoke then will not vibrate into the beam of light. Accordingly, it is a further object of my invention to provide improved apparatus of the foregoing character for properly fixing the orientation of a watch balance wheel relative to the vibration counting apparatus irrespective of where the hair spring is held.

In carrying out the invention in one form, apparatus for timing a hair spring and the attached balance wheel including a spoke is provided comprising a hard surface upon which one end of the balance wheel shaft is adapted to pivot, means for gripping a watch spring at some point along its length to support the balance wheel shaft on said hard surface, a counter, photoelectric means operative when said balance wheel vibrates to actuate the counter, and timing means for predetermining the interval of counter operation.

For a more complete understanding of the invention, reference should be had to the accompanying drawings in which:

Figure 1 is a front view of hair spring and balance wheel vibrating apparatus embodying the invention;

Fig. 2 is a side view partially in section of the apparatus shown in Fig. 1;

Fig. 3 is a top view taken substantially in the direction of the arrows 3-3 of Fig. 2;

Fig. 4 is a view on a larger scale taken substantially in the direction of the arrows 4-4 of Fig. 3;

Fig. 5 is a view taken substantially in the direction of the arrows 5-5 of Fig. 4;

Fig. 6 is a top view on an enlarged scale of the hair spring gripping mechanism;

Fig. 7 is a sectional view taken substantially in the direction of the arrows 7-7 of Fig. 6;

Fig. 8 is a side view on an enlarged scale of a modified form of hair spring gripping mechanism;

Fig. 9 is a sectional view taken substantially in the direction of the arrows 9-9 of Fig. 8;

Fig. 10 is a diagrammatic representation of the apparatus embodying the invention;

Fig. 11 is a fragmentary view of the counting mechanism, and

Fig. 12 is a fragmentary view on an enlarged scale of the timing mechanism.

Referring to the drawings, the invention is shown as embodied in a timepiece hair spring and balance wheel vibrating and counting apparatus

10 comprising a frame 11 supporting in operative relationship with each other a photoelectric pickup 12, a housing 13 containing a relay and amplifier cooperating with the photoelectric pickup, and a sub-housing 14 enclosing timer mechanism 15, a counter 16, a light source 17, and supporting hair spring gripping and moving means 18. The light source 17 provides a beam of light received by the photoelectric pickup, which beam of light is interrupted or modified by the spoke of a balance wheel. These interruptions or modifications give rise to impulses which are received by amplifying and relay apparatus 13 and in turn energize counter 16 to count the number of vibrations which the balance wheel makes, the timing apparatus 15 being adapted to stop the functioning of the counter after a predetermined length of time, as will be more fully explained.

The sub-housing 14 includes a removable cover 19 substantially centrally of which there is provided an opening having a stepped edge within which is received a circular disc 21 of a smooth, hard material such for example as glass. A small opening at the center of disc 21 is fitted with a metal bushing 22 for determining the dimensions of the light beam from light source 17. The surface of plate 21 forms a bearing for one end of the shaft or verge of a balance wheel 23, while the balance wheel and the combined hair spring 24 are supported by having one end of the hair spring held or gripped by the jaws 25. The gripping jaws are prevented from interfering with the action of a hair spring during vibrating movements thereof, inasmuch as the gripping jaws are raised vertically by the mechanism 18, causing the hair spring to take an inverted conical form, as may be seen best in Fig. 4 whereby the second hair spring coil lies below the gripping jaws and does not come into contact therewith during the vibrating movements. The photoelectric pickup 12, enclosing a photocell 10, and the light source 17 are so oriented relative to each other than the beam of light 26 passes inside of the balance wheel rim and yet avoids the coils of the hair spring.

The mechanism 18 for gripping and holding the hair spring and attached balance wheel consists of a vertical stud 27, a rack 28 movable vertically relative thereto by a pinion 29, a rack 31 supported on rack 28 and movable horizontally relative thereto by a pinion 32, a downwardly extending shaft or post 33 pivotally mounted at the outer end of rack 31 and a yoke 34 extending horizontally from, and attached to, post 33, the gripping jaws 25 being supported at the outer end of yoke 34.

Vertical stud 27 is rigidly attached to a thin annular ring 35 rotatably mounted in a groove in top member 19, ring 35 being held within the groove by any desired means, such for example as the heads of screws 36, as shown. By virtue of pinion 29 supported relative to rack 28 by straps 37, which also hold rack 28 relative to stud 27, the rack 28 is vertically movable by means of a knob 38. Vertical movements of rack 28 carry rack 31 and thus the yoke 34 and gripping jaws 25 vertically. Sufficient friction exists between the various parts to hold rack 28 in any vertical position. Hence, the position of the gripping jaws relative to the hair spring coils may be adjusted vertically as desired while still having the lower end of the balance wheel verge bear lightly on the surface of disk 21. Radial movements of rack 31 effected by pinion 32 and the associated knob 39 bring the balance wheel into the desired

radial position relative to the opening through bushing 22. Rack 31 is supported atop rack 28 by means of pinion 32 and strap members 41, as shown, and sufficient friction exists between the members to hold rack 31 in any position.

The end of a hair spring chosen at random may bear any directional relationship to the position of the balance wheel spoke. To bring about the desired position of the balance wheel spoke 43, ring 35 may be moved circumferentially (i.e., rotated around its center) and yoke 34 may be pivoted about stud 33 as a center by means of knob 42 attached to the stud. In Figs. 3 and 5 spoke 43 is shown in one position of operation by the solid lines. In Fig. 3 the structure 18 is shown in a second position by the dotted lines. It is evident that the position of spoke 43 is also changed relative to the opening in bushing 22. To obtain proper functioning of the apparatus, it may be found that the beam of light should be interrupted from the side rather than from the front. Hence, if the position shown by the dotted lines was the first one obtained, then it is obvious that the position of the mechanism may be changed to that shown by the solid lines. In Fig. 5 yoke 34 is shown in a second position by the dotted lines. If perchance the initial position of the yoke 34 with the attached balance wheel is that shown by the dotted lines where spoke 43 is far from bushing 22, evidently it may be moved to the position shown by the solid lines. The combination of the circumferential movements of ring 35, pivotal movements of yoke 34, and radial movements of rack 31, bring the spoke 43 of any balance wheel into the proper position relative to the light beam 26. Balance wheels of different diameters may be accommodated by the radial movements of rack and pinions 31 and 32.

The yoke 34 comprises a pair of flat plates 44 and 45 spaced apart by posts 46 and held thereto by screws 47. Plates 44 and 45 are generally sector shaped with resilient tongues at one end, the tongues having holes through which the lower end of post 33 may be received. In alignment with the holes through the tongues is a sleeve 48 serving to space the fingers apart. The yoke 34 is held to the stud by the friction between the holes through the tongues and the post, and will turn therewith whenever the post is rotated by means of knob 42. The upper plate 44 is smaller than lower plate 45, as may be seen best in Figs. 3, 4 and 5.

At the outer end thereof and adjacent the left side of lower plate 45, is an upwardly bent member 49 having a hole therethrough within which is received the base 51 of the structure forming gripping jaws 25. Member 49 is sufficiently rigid and firmly attached to plate 45 so that it will remain in its vertical position, and the base 51 is firmly attached to member 49 such as by a press fit or other suitable means, for example, soldering.

The spring gripping structure, including jaws 25 and base 51, preferably may be formed as a unitary structure and as shown, base 51 is a hollow cylindrical member and the jaws 25 are flat members formed by machining away a portion of the cylindrical material. The jaws are separated by a very thin split 52, but normally the jaws are closed with their faces directly abutting each other due to the resilience of the jaw members. A tube 53 is slidably received within base 51 and is provided with a rounded front edge 54. The inside surfaces 55 of the jaw members, against

which the front edge 54 abuts, are also curved or tapered so that when the front edge 54 is forced against surfaces 55 during operation of the structure, the jaw members are forced apart, and when front edge 54 of the above is moved away from surfaces 55 the jaws come together. Sleeve 53 may be moved rearwardly or forwardly by means of a probe inserted into a conveniently provided hole 60.

10 A radial bar 56 is pivotally mounted at its rear end adjacent the rear portion of plates 44 and 45 on a shaft 57 and extends forwardly so that it protrudes beyond the extremity of upper plate 44. The outer end of bar 56 includes a thumb screw 58 and a hole 59 so that the inner end of the thumb screw may be visible. A horizontal hole intersecting with hole 59 is also provided through the outer end of bar 56.

15 The jaw gripping structure and bar 56 held by yoke 34 operates as follows: Referring more particularly to Figs. 5 and 6, the hair spring 24 is shown gripped by jaws 25. The hair spring passes through tube 53 and the inner end thereof is received through the horizontal hole in the outer end of bar 56 and is clamped thereto by means of the thumb screw 58. When it is desired to change the gripping position on the hair spring to shorten it, tube 53 is pushed forwardly to hold jaws 25 apart and bar 56 is moved clockwise to pull the hair spring 24 through the jaws. After the desired movement is made, tube 53 is moved toward the right, whereupon the jaws again grip the spring. When it is desired to lengthen the spring, tube 53 is again moved forwardly to release the gripping jaws and bar 56 is moved counterclockwise to push the hair spring outwardly through the gripping jaws until the desired position is reached, whereupon tube 53 is again moved toward the right whereupon the jaws grip the spring. The slit 52 between jaws 25 is perfectly straight and formed so as to lie in line with the axis of tube 53 so that when spring 24 is gripped it may be gripped along the tangent thereto so as not to injure it.

20 25 30 35 40 45 50 55 60 65 70 75 80 85 90 95 100 With the structure as thus far described, hair spring 24 may be gripped at any desired point and the hair spring and balance wheel may be moved into position relative to bushing 22 so that the balance wheel spoke 43 may vibrate across or into the beam of light coming through bushing. Moreover, the vertical position of the hair spring may be so adjusted that the balance wheel shaft rests on the surface of member 21 and also remains out of the line formed by light beam 26. When the hair spring is so gripped, it may be set into motion by means of a probe and with the apparatus to be described the number of vibrations may be counted.

Referring to Fig. 10, there is shown a schematic diagram of the complete apparatus for counting the vibrations of the balance wheel 23 once it has been set in motion. The balance wheel is so set that its spoke vibrates into the beam of light 26 formed by the incandescent source 17 shown as a conventional lamp supplied with current through the transformer 59, the light beam falling upon a photoelectric cell 70 (supported in pickup 12, Figs. 1 and 2), the signals from which are fed to an amplifier 61 through conductors 62 and 63. The amplified signals are fed to a coil 64 of a relay 65 through conductors 66 and 67, the relay including a pair of contacts 68 which, when closed, are adapted to energize counter 16.

75 Electrical power for the timing and counting

operation is supplied from a voltage source 80 which, for example, may be 110 volt alternating current. When it is desired to start the apparatus functioning, a switch 69 is closed thereby supplying power to amplifier 61 through the circuit beginning with source 80 and including the conductors 71, 72, 73, 74, 75, 76, the fuse 77, and the conductors 78 and 79. On completing this same circuit, a circuit is completed to a signal light 81 through conductors 82 and 83, the signal lamp indicating that the amplifier is receiving current and is heating up, and consequently after a short interval the apparatus is in condition to function. Closing switch 69 also completes a circuit to transformer 59 from source 80 through conductors 71, 72, 84, 85, through primary winding 86 of the transformer, through conductors 87, 75, 76, fuse 77, and conductors 78 and 79. Consequently, light source 17 is energized and the beam of light 26 is in existence.

Timer 15, shown enclosed in Figs. 1 and 2, is illustrated schematically in Fig. 10 as comprising the synchronous motor 88, a train of gears 89, a cam 91, and a pointer 92. The train of gears 89 is connected by means of a shaft to synchronous motor 88, and the last gear 93 of the train is connected by means of a frictional clutch and shaft to cam 91 and pointer 92. Referring to Fig. 12, pointer 92 is shown fixed to a shaft 94 by a set screw 95, which however is only exemplary. The other end of shaft 94 is attached to gear 93 by means of a flat plate 96 and bowed plate 97, these plates holding gear 93 to shaft 94 by means of riveting over the end of the shaft. Due to the bowing of plate 97, plates 96 and 97 grip gear 93 relatively lightly so that pointer 92 may be turned without turning gear 93 inasmuch as this gear is coupled through the gear train 89 to the synchronous motor. But when gear 93 is rotated by the synchronous motor, pointer 92 and cam 91, also firmly attached to shaft 94, rotate therewith. Cam 91, in its periphery, is provided with a notch 98 adapted to receive a corresponding protuberance 99 on a leaf spring 101, the leaf spring being provided with a contact 100 at one end for engagement with a contact 100a connected to a conductor 102. Associated with pointer 92 is a dial plate 103 graduated in any units, for example minutes, and as shown is graduated from 0 to 6 minutes.

Synchronous motor 88 is adapted to run always in the same direction which is such that pointer 92 moves clockwise. Thus, if pointer 92 is moved to 1 minute, cam 91 is rotated so as to move protuberance 99 out of notch 98 and thereby close contacts 100 and 100a. Then, if motor 88 is energized, as will be described subsequently in this specification, the operation of the motor causes pointer 92 to move from 1 towards 0, cam 91 moving correspondingly, and when the pointer reaches 0, notch 98 will receive protuberance 99 and thereby open the contacts since spring 101 is resiliently made. Cam 91 and pointer 92 are fixedly mounted relative to each other so that the rotation of notch 98 to a position indicated by moving the pointer to any number on dial 103 determines the length of time the synchronous motor runs before notch 98 is returned to a position where it will receive protuberance 99. Inasmuch as synchronous motor 88 always runs at the same speed, it is apparent that the distance cam 91 has to rotate to effect opening of contacts 100 and 100a, is indicative of the time elapsed.

Synchronous motor 88 may be energized to be-

gin the timing operation only after pointer 92 has been turned to a desired position, for Example 1 on dial 103, the switch 69 has been closed to warm up the amplifier and to form beam of light 26, and balance wheel 23 has been set in motion. Thereafter switch 104 is closed which energizes motor 88 and also the actuating mechanism of counter 16 so that the timing and counting operations begin at the same time. The circuit for energizing motor 88 is as follows: From source 80 through conductors 71, 72, 105, the winding of motor 88, conductors 106 and 102, contacts 100a, 100, spring 101, conductor 107, switch 104, conductor 108, fuse 77, conductor 98, switch 69, and conductor 79 to source 80. Counter 16 is actuated by an electromagnet including coil 109 energized also after switches 69 and 104 have been closed through the following circuit: From source 80 through conductors 71, 72, 84 and 110, coil 109, conductor 111, contacts 68, conductors 112, 106 and 102, contacts 100a, 100, spring 101, conductor 107, switch 104, conductor 108, fuse 77, conductor 98, switch 69, and conductor 79 to source 80. The contacts 68 of relay 65 are intermittently closed by impulses from amplifier 61 as photoelectric cell 70 intermittently has its light cast off or decreased due to the vibration of balance wheel 23. The circuit described for counter coil 109 is completed only when contacts 68 are closed and consequently the actuating mechanism of counter 16 is intermittently energized. The circuit for coil 109 and the circuit for motor 88 are not completed until switch 104 is closed, and are not effected by closing of switch 69.

When switch 104 is closed, a circuit is completed also to a second indicating lamp 113 which indicates that the complete mechanism is functioning. The circuit for lamp 113 is completed as follows: From source 80 through conductors 71, 72, 84, 85 and 114 to lamp 113, and therefrom through conductors 115 and 102, contacts 100a, 100, spring 101, conductor 107, switch 104, conductor 108, fuse 77, conductor 98, switch 69, and conductor 79 to source 80.

The counter 16 is of a type comprising a series of round members 116 bearing numbers from 1 to 9 and 0 thereon. Associated with members 116 is a lever 117, a ratchet wheel 118, and a pawl 119 biased by a spring 121 to engage the ratchet wheel. At one end of lever 117 there is a link member 122 forming the core of coil 109, link 122 being biased in the direction shown by a compression spring 123. Whenever coil 109 is energized, lever 117 is moved counterclockwise, thereby moving one of the indicating wheels 116 a distance of one number, this being accomplished by the closing of contacts 68. When contacts 68 open, energization is removed from coil 109 whereby spring 123 urges the lever 117 to its normal position where pawl 119 can engage ratchet wheel 118 in a new position. In Fig. 11 the face view of the counter has been shown. The elements of the counter as described are well known, and thus are not disclosed in greater detail.

The operation of the completed device is as follows: It is assumed that the watch hair spring 24 has been placed into gripping jaws 25 and the position thereof and of the balance wheel 23 adjusted so that the spoke 43 comes into approximately the proper position relative to bushing 22. At this point switch 69 may be closed thereby energizing amplifier 61, photoelectric cell 70, and signal light 81. The lighting of signal light 81 indicates that the apparatus is turned on and about ready to function. After a small interval

of time, for example, several minutes, have elapsed allowing the amplifier to warm up, pointer 92 may be turned to any position, for Example 1 on dial 103, this movement causing cam 91 to rotate a corresponding distance and thereby close contacts 100, 100a, these contacts being open when protuberance 99 is received within notch 98. Now the balance wheel 23 is set into vibration bringing spoke 43 into light beam 26, and switch 104 is closed. At the closing of this switch, signal light 113 comes on indicating that the counting and timing function is under way. Also at the closing of switch 104 synchronous motor 88 begins to run and energization is supplied to coil 109 whenever the contacts 68 are thereafter closed. With each vibration of spoke 43 into the beam of light, an impulse is received at the amplifier which is amplified and passed on to coil 64 whereby the relay 65 intermittently closes contacts 68. While motor 88 rotates in a direction moving the notch 98 toward the protuberance 99, i. e., timing the interval of operation, counter coil 109 is receiving the impulses and moves one of the wheels one notch with each closure of contacts 68.

The foregoing operations take place simultaneously so that counter 16 counts the number of movements of the balance wheel while synchronous motor 88 is timing the operation. When notch 98 reaches the protuberance 99 the contacts 100 and 100a open, thereby de-energizing motor 88, and at the same time removing energy from coil 109 thereby simultaneously stopping the timing and counting operations. The end of the timing operation is indicated when the pointer 92 has returned to 0 whereupon signal light 113 also goes out.

The operation described is a timing operation of one minute and during this time, depending upon the adjustments of the hair spring relative to the gripping jaws, as many as 300, or more or less, vibrations could have been counted by counter 16. Before making a regular timing operation as described, the apparatus may be set into operation by moving the pointer 92 to any desired position and closing switch 104 in order to adjust the position of the balance wheel spoke so that it comes into, crosses, or merely interferes with the beam of light as much as is necessary to get a sufficient variation in the light intensity to cause the apparatus to function properly.

If the point of gripping the hair spring has been such that too many vibrations were made, the hair spring is lengthened as described, the counting operation is then repeated, and as many similar tests made until the desired length is obtained. After the proper gripping point is obtained, the hair spring may be bent sharply at an angle across the front surface of the gripping jaws thereby determining the exact location where the hair spring should be gripped after it is placed in the timepiece. In the manner described, an exact count of the number of vibrations is obtained inasmuch as the photoelectric cell is sensitive and can pick up variations in the amount of light caused by the balance wheel spoke, and relay 65, together with the counting mechanism, is sufficiently accurate and sensitive to function as many as six or more times per second. Counting the actual vibrations is an exact method of determining the point at which the hair spring should be gripped since it does not involve the accuracy of a standard of comparison, the number of vibrations which a balance wheel has to make being accurately known

from the number of teeth on the various time-piece gears.

Referring to Figs. 1 and 2, the arrangement of the parts described in connection with Fig. 10 may be seen. Photoelectric cell 70 is mounted in pickup 12 and is attached to frame 11 by means of a stand 138. The pickup 12 is attached to this stand by means of a bolt and wing nut 124 so that the angle of the pickup may be changed if necessary for the beam of light 26 to squarely impinge upon the photo-sensitive surface of the photo cell. The housing 13 contains the amplifier 61 and the relay 65 which are of well known construction and are not disclosed in detail in this specification. While cover 19 of subhousing 14 holds mechanism for gripping and movably supporting the watch hair spring and balance wheel, the inside thereof houses the various other mechanisms. Thus, for example, the transformer 59 is adapted to support the socket 125 holding incandescent lamp 11. The counter 16 is arranged at one end of the housing alongside fuse 17 and the timer 15 is arranged at the front of the apparatus with pointer 92 externally visible. Also externally visible are the indicating lights 81 and 113 together with the off and on buttons for switches 69 and 104 respectively.

In Figs. 8 and 9 there is shown a modified structure for holding the gripping jaws. In this structure there is provided a hollow cylindrical member 126 within which are mounted a pair of rubber-rimmed rollers 127 and 128, the shaft 159 of roller 128 coming out and being provided with a knurled turning knob 131. Cylindrical member 126 is closed on each side by plates 132 and 133 which also provide bearing surfaces for the shafts of rollers 127 and 128. Plates 132 and 133 have tongues 134 and 135 extending from each end and corresponding to the tongues at the end of yoke 34. Holes are provided in tongues 134 and 135 for receiving the lower end of stud 33, as already described. Cylindrical member 126 is provided with holes 136 and 137, hole 136 being adapted to tightly receive the base 51 of the gripping jaw structure, this being by a press fit or by soldering, for example. The hair spring to be gripped by jaws 25 is passed through the tube 53 and is received between the engaging surfaces of rollers 128 and 127, the end of the spring passing out through hole 137. When it is desired to change the position of the hair spring, it is only necessary to release jaws 25 and turn knob 131 thereby moving the hair spring either to lengthen it or shorten it, as the case may be. When the desired change has been made, the tube 53 is moved to allow the jaws to grip the spring at the new point.

While particular embodiments of the invention have been shown, it will be understood, of course, that the invention is not limited thereto since many modifications may be made, and it is, therefore, contemplated by the appended claims to cover any such modifications as fall within the true spirit and scope of the invention.

Having thus described the invention, what is claimed and desired to be secured by Letters Patent is:

1. Apparatus for counting the vibrations of a hair spring and the attached balance wheel including a spoke comprising, a pair of expandable jaws for gripping said hair spring, means for expanding said jaws for releasing the grip thereof on said hair spring, an electric eye device including a beam of light, a pivotal support for

said jaws, first rack and pinion means for supporting and radially moving said pivotal support, second rack and pinion means for holding and vertically moving said first rack and pinion means, means movable about a circular path substantially centered about said expandable jaws for supporting said second rack and pinion means, said pivotal support, said first and second rack and pinion means, and said circularly moving means cooperating to permit movement of said jaws whereby the spoke of said balance wheel may be made to vibrate through said beam of light, a counter controlled by said electric eye device for counting the number of times said spoke vibrates into said beam of light, and timer means for predetermining the interval of counter operation, said timer means comprising an electric motor and switch means for de-energizing said motor after a certain number of revolutions.

2. Apparatus for timing a hair spring and an attached balance wheel including a spoke comprising, a device for gripping said hair spring at some point along its length, electric eye apparatus including a beam of light, a counter controlled by said electric eye apparatus, means for predetermining the interval of counter operation,

and adjustable supporting means for said gripping device, said supporting means permitting pivotal movement of said gripping device about a pivot having a vertical axis and linear movement of said pivot along a horizontal straight line, said gripping means having a pair of jaws for releasably holding said spring at any desired point thereon and a hollow tube arranged with one end thereof opening immediately behind said jaws for receiving and positioning the inactive end of said spring.

FORREST JULIAN CALDWELL.
